UNITED STATES PATENT OFFICE.

ROMEO A. BEAUMETTE, OF CHIPPEWA FALLS, WISCONSIN.

CLAMPING DEVICE.

1,078,533.

Specification of Letters Patent. Patented Nov. 11, 1913.

Application filed February 7, 1913. Serial No. 746,799.

To all whom it may concern:

Be it known that I, ROMEO A. BEAUMETTE, a citizen of the United States, residing at Chippewa Falls, in the county of Chippewa and State of Wisconsin, have invented certain new and useful Improvements in Clamping Devices, of which the following is a specification.

The tool of the present invention is designed particularly for clamping purposes, the main object in view being to provide an effective device capable of clamping wire or similar encircling bands to articles requiring the same.

15 The simplicity of my construction is an advantageous feature in its production, the aim being to so form the tool that the wire may be made into a clamp, then adjusted, and finally applied in proper manner.

20 For a full understanding of the present invention, reference is to be had to the following description and the accompanying drawings, in which—

Figure 1 is a side elevation of a device 25 constructed in accordance with my invention, and showing its application. Fig. 2 is a plan view of the same. Fig. 3 is a longitudinal sectional view on the line 3—3 of Fig. 2. Fig. 4 is a transverse section on the 30 line 4—4 of Fig. 3.

Throughout the following detail description and on the several figures of the drawings, similar parts are referred to by like reference characters.

35 In the preferred embodiment of my tool, as illustrated in the drawing, the numeral 1 designates the body portion which is hollow throughout the greater portion of its length, or tubular in form. The lower end 40 of this body portion is preferably reduced as denoted by the reference character 2, while its end is provided with a transverse groove 3 or concaved for a purpose herein-after set forth. At opposite sides and sub- 45 stantially centrally of the same, the hollow body 1 is formed with longitudinally ex-tending slots 4 adjacent which, or near its upper end, are formed laterally projecting arms 5 constituting a finger grip for facil- 50 itating use of the tool.

Into the hollow body 1 extends a stretching rod 6 threaded at its outer end 7, which projects slightly beyond the end of the body 1, to receive the adjusting nut 8 which is 55 adapted to seat or bear against the end of

the body in the performance of the stretching function. The lower or inner end portion of the rod 6 is provided with a transverse bore in which is inserted a pin or cross rod which projects through the guiding slots 60 4 and forms the laterally extending wire engaging arms 9.

In the use of my invention, and describing its clamping action in reference to making hose connections, or the like, a piece of 65 doubled wire 10 of suitable length, is passed around the hose or article 11, the free ends of the wire being brought up between the doubled or looped portion as shown in Figs. 1 and 2. The concaved end of the tool is 70 then laid against the doubled end of the wire, while the free ends of the latter are wrapped one or more times around the arms 9 carried by the stretching rod 6. By turning the nut 8 in one direction the rod 6 is 75 pulled outwardly firmly drawing the ends of the wire through the loop formed by doubling and when enough pressure has been provided the tool is moved bodily in a lateral direction into a position substan- 80 tially as shown by dotted lines in Fig. 1. The clamp is thus secured about the article and the free ends of the wire are slipped laterally off the arms 9 and cut the desired length. 85

One of the main points of advantage of my form of device is the ease with which the ends of the wire may be disengaged from the arms of the stretching rods and it will be quite obvious that adjusting of the tool 90 is quickly accomplished, requiring mainly the wrapping of the wire around the arms and adjustment of the nut 8 to perform the desired result. The arms 9 coöperate with the slots 4 to guide the stretching rod 6 95 in its movement and also provide a connection of the parts of the tool.

Slight changes may be made in the details of construction of my invention without departing from the spirit of the same 100 and within the scope of the appended claim.

Having thus described the invention, what is claimed as new is:

A tool of the class described comprising 105 a hollow body portion having diametrically opposing longitudinal slots formed intermediate its length, a stretching rod movable within the hollow body portion, laterally projecting wire engaging arms carried by 110

the stretching rod and extending through the slots aforesaid, the arms coöperating with the slots to guide the stretching rod, and an adjusting nut threaded upon the stretching rod and having its bearing against the body portion to move said rod longitudinally of the body portion.

In testimony whereof I affix my signature in presence of two witnesses.

ROMEO A. BEAUDETTE.
